UNITED STATES PATENT OFFICE.

JOHANNES JACOBUS HENDRIKUS WILHELMUS WEELEN, OF AMSTERDAM, NETHERLANDS, ASSIGNOR OF ONE-THIRD TO KAREL WILLEM GERARD JOHAN STOFFELS AND ONE-THIRD TO JAN BERKELBACH VAN DER SPRENKEL, BOTH OF AMSTERDAM, NETHERLANDS.

CONTACT DEVICE.

1,072,540.

Specification of Letters Patent.

Patented Sept. 9, 1913.

Application filed November 23, 1912. Serial No. 733,184.

To all whom it may concern:

Be it known that I, JOHANNES JACOBUS HENDRIKUS WILHELMUS WEELEN, subject of the Queen of the Netherlands, residing at 5 Amsterdam, in the Netherlands, have invented certain new and useful Improvements Relating to Contact Devices, of which the following is a specification.

This invention relates to contact devices 10 for controlling points or signals on electric tramways and the like and has particular reference to the type of point-setting apparatus for electric tramways where a "line contactor" is employed with which the trolley-wheel or other current collector engages 15 just before the points are set. Like other point-setting apparatus of this type part of the line contactor is in the form of a member which can be moved by the wheel or 20 other current collector, but according to the present invention the movement of this member tends to close two contact arms in circuits which include the solenoids or electromagnets which operate the points. If they 25 were not prevented both these contact arms would be operated, but the improved apparatus also comprises a solenoid having a core which, according to its position, prevents 30 one or other of the arms from completing its movement. The other arm, which is not obstructed by the core, closes its circuit and the point is set. Thus the solenoid acts as a selector to determine which of the circuits shall be closed. The contact arms are 35 preferably, each in two parts, normally kept in line by a spring, so that they tend to move as one arm; but an obstruction in the path of the upper part of either arm, will cause that portion to be retained, while the movement of the lower part is completed. The 40 solenoid is preferably arranged so as to lie transversely to the planes in which the contact arms move and, as will be more particularly described later on, when once the solenoid has been set by the conductor running 45 on to the line contactor, the arm which is operative forms a stop for the core of the solenoid and prevents the driver of the vehicle from altering the arrangements if he 50 makes or breaks the current while the vehicle is passing the apparatus.

In the accompanying drawings, Figure 1 is a side elevation showing the whole apparatus according to one construction of this

invention in its normal position before it 55 is operated by the current collector. Fig. 2 is a similar view of the contact arms and solenoid drawn to a larger scale. Fig. 3 is an elevation similar to Fig. 2 but with the parts in one of the positions they assume 60 when a current collector is passing the apparatus. Fig. 4 is a plan of the apparatus in the position shown in Fig. 3, and Fig. 5 is an elevation showing a modified form of the apparatus for use with a bow collector 65 instead of a trolley-wheel.

Like letters indicate like parts throughout the drawings.

With reference first to Figs. 1, 2, 3 and 4, the ordinary overhead conductor A has secured to it by clamps side rods B and a running rod C, these are insulated from the conductor A by washers as at D. Inclined guides E are also provided attached to the overhead conductor and serving to lead the 70 trolley-wheel or other collector from the conductor to the running rod C or vice versa. Suspended from the side rods B by links F' is a member F in the form of a strip of metal so disposed relatively to the 75 running rod C that it will be engaged and lifted or swung by the flanges of the trolley-wheel G when it passes beneath it. On the spindle F² of one pair of the links F' are mounted two contact arms H H'. The 80 lower part H of each of these arms is fixed to the spindle, but the upper portion H' can turn about the spindle but is normally kept in line with the lower part by a spring H². Thus when the member F is moved by the 85 trolley-wheel the links F', which are fixed to the spindle F², turn and rotate the spindle and the arms H H' turn also. Mounted transversely to the conductor A and rods B is a solenoid J having a core J' normally 90 caused by a spring K to project outside one end of the solenoid i. e. the lower end of the solenoid as seen in the plan forming Fig. 4. At the other end, the core is furnished with a non-magnetic extension J² which projects 95 from the solenoid when it is energized in the position shown in Fig. 4. Thus one end or the other of the core is always projecting and the relative positions of the solenoid J and the contact arms H H' are such that the 100 upper portion H' of the arm on the side at which the core projects is obstructed by the core and cannot follow the motion of the 105

lower part H when it is turned. Thus the solenoid acts to determine which of the arms H H' shall be operative. Coöperating with each contact arm H H' is a fixed contact L 5 adjustably mounted on an insulating support M on the side bars B and when an arm H H' is free to turn it completes a circuit by making electrical connection with the corresponding fixed contact L. These circuits are 10 not shown, but it will be understood that they may be those of any well known point- or signal-operating solenoids, or magnets, or like electromagnet apparatus of which there are many examples. For instance, one contact arm may control the circuit of a solenoid or electromagnet acting, when energized, to move or set the rail-points for a straight course and the other contact arm may similarly control another solenoid 15 20 which sets the points for a curve. Or again, the circuits controlled by the contact arms may contain electromagnets which operate signals or other apparatus. The winding of the solenoid J is connected at 25 one end to the conductor A and at the other end to the running rod C and thus if when a vehicle passes under the apparatus the driver keeps his switch on, current passes from the conductor A, through the solenoid 30 thence through the running rod C and the trolley-wheel G, to the controller and motors of the vehicle. Consequently the solenoid is energized and its core is pulled back against the action of the spring K, causing 35 the end J² to project as shown in Fig. 4. The movement of the member F imparted to it by the flanges of the trolley-wheel G causes the contact arms H H' to turn toward the contacts L. One of the arms is unob- 40 structed and consequently moves forward until it touches the fixed contact L, but the other arm can not complete its movement owing to the projection of the core which is in the path of motion of the upper part H' 45 of the arm. This position of the apparatus is shown in Figs. 3 and 4 where the contact arm H H' on the far side of the solenoid is shown as obstructed by the end J² of the core. Supposing the driver cuts off the cur- 50 rent to the vehicle when it is passing the line contactor, then the solenoid is not energized, its core will not be pulled back and consequently the contact arm H H' on the near side of the solenoid as shown in Fig. 3 will 55 be prevented from closing down on to its contact L and the contact arm on the far side of the solenoid will turn right down and complete its circuit. On reference to Fig. 3 it will be seen that when one of the contact 60 arms is turned down to make connection with its fixed contact L, the upper portion H' of the arm lies in the path of the end of the core J'. The object of this arrangement is to prevent any reversal of the initial posi- 65 tion of the solenoid by the driver altering

the electrical connections to the vehicle and either "making" the circuit when he has passed on to the line contactor with the circuit off, or breaking the circuit when the current was on in the first instance.

The construction shown in Figs. 1, 2, 3 and 4, is adapted for use with a current collector in the form of a trolley-wheel, but obviously the apparatus can be modified to render it available with a bow collector. Such a 70 modification is illustrated diagrammatically in Fig. 5 where the member F is replaced by a flat bar F³ hung, as in the other construction on links and adapted to be displaced by the bow collector which is shown 75 in section at G.

A slight rubbing action between the contacts on the arms H H' and the fixed contacts L, may be secured by suitably adjusting the inclination and position of the fixed 80 contact.

If the vehicle passes the apparatus in the other direction *i. e.* from left to right of the drawings neither of the contact arms will be operative.

Although the apparatus according to this invention is illustrated as applied to an overhead conductor, yet obviously by modifying the mechanical details it can be used with a conduit system suitable arrangement 90 being made whereby the shoe depresses moves mechanism corresponding to the member F and thus operates two contact arms, a solenoid or electromagnet determining which of those arms is effective in 100 completing a circuit.

What I claim as my invention and desire to secure by Letters Patent is:—

1. In electrically operated point- or signal-controlling apparatus for tramways 105 and the like the combination of a member adapted to be moved by the trolley-wheel or other current collector, a plurality of contact arms operatively connected to such member, point- or signal-controlling circuits 110 controlled by said contact arms and electro-magnetic means acting, to determine which of said contact arms shall complete its circuit.

2. In electrically operated point- or signal-controlling apparatus for tramways and the like the combination of a member adapted to be moved by the trolley-wheel or other current collector, a plurality of contact arms operatively connected to such member, point- or signal-controlling circuits 115 controlled by said contact arms and electro-magnetic means acting to prevent one of said contact arms from completing its circuit.

3. In electrically operated point- or signal-controlling apparatus for tramways and the like the combination with point- or signal-controlling circuits of two contact arms controlling said circuits, and a sole. 130

noid or electro-magnet having a core which projects into the path of motion of one or other of the contact arms for the purpose set forth.

5. 4. In electrically operated point- or signal-controlling apparatus for tramways and the like the combination of a solenoid, a core for such solenoid adapted to project at one end or the other of the solenoid 10 according to whether the solenoid is energized or not and two contact arms movable across the path of motion of the core and each comprising two parts pivoted and spring-controlled so that they move together if the path is not obstructed by the core but can move relatively if the core obstructs the motion of one part.

5. In electrically operated point- or signal-controlling apparatus for tramways 20 and the like the combination of an overhead conductor, a member suspended by links and adapted to be moved by the trolley-wheel or other current collector, two contact arms operatively connected to the member each contact arm comprising two parts normally spring-controlled and moving together, adjustable means for preventing simultaneous movement of both contact arms, and a solenoid controlling the position of said means relative to the contact arms.

6. In electrically operated point- or signal-controlling apparatus for tramways and the like the combination of an overhead conductor a member suspended by links and adapted to be moved by the trolley-wheel or other current collector, a plurality of contact arms operatively connected to the member each contact arm comprising two parts normally spring-controlled and moving together a solenoid and a spring-controlled core such core projecting into the path of motion of one or other of said contact arms according to whether the solenoid 45 is energized or not.

7. In electrically operated point- or sig-

nal-controlling apparatus for tramways and the like the combination of an overhead conductor, a member suspended by links and adapted to be moved by the trolley-wheel or other current collector, a plurality of contact arms operatively connected to the member each contact arm comprising two parts normally spring-controlled and moving together a solenoid and a spring-controlled core such core projecting into the path of motion of one or other of said contact arms according to whether the solenoid is energized or not the relative disposition of the core and the contact arms being such that the arm which is unobstructed by the core acts, when in its closed position, as a stop to prevent the movement of the core while the vehicle is passing the apparatus.

8. In electrically operated point- or signal-controlling apparatus for tramways and the like the combination with point- or signal mechanism controlling circuits of an overhead conductor, side rods and a running rod 70 clamped thereto but insulated therefrom, a member suspended by pivoted links from the side rods and adapted to be moved by the flanges of the trolley-wheel when the trolley is on the running rod, contact arms 75 operatively connected to the member and controlling said circuits, a solenoid mounted on said side rods and a spring-controlled core for such solenoid said core being adapted to project across the path of motion of one or other of the contact arms according to whether the solenoid is energized or not.

In testimony whereof I have signed my name to this specification in the presence of 85 two subscribing witnesses.
